SECURING MEANS FOR TANK CAPS

Frank Macagno, San Francisco, Calif., assignor of
one-fourth to Eugene Taldo, Los Angeles,
Calif.

Application November 12, 1937, Serial No. 174,230

1 Claim. (Cl. 292—144)

This invention appertains to new and useful improvements in means for locking tank caps such as the caps of gasoline tanks located on automobiles.

5 The principal object of the present invention is to provide a tank cap which can be secured or unsecured conveniently from a position convenient to the driver.

10 Another important object of the invention is to provide a cap lock of the character stated which will utilize but a very small amount of electricity.

15 Still another important object of the invention is to provide a cap lock which is of simple construction and not susceptible to the ready development of defects.

15 Other important objects and advantages of the invention will become apparent to the reader of the following specification.

In the drawings:

20 Figure 1 represents a fragmentary side elevational view showing the tank cap and lock means with the latter partly in section.

Figure 2 is a sectional view taken substantially on the line 2—2 of Figure 1.

25 Figure 3 is a fragmentary plan view with portions in section and removed.

Figure 4 is a bottom plan view of the cap.

Figure 5 is a side elevational view of the cap.

30 Figure 6 is a diagrammatic view disclosing the electrical connections between the electrical devices involved.

35 Referring to the drawings wherein like numerals designate like parts, it can be seen that numeral 5 denotes the tank neck while numeral 6 generally refers to the cap.

35 As is well known, the upper portion of the neck 6 is flanged inwardly as at 7 and bent downwardly and this flange is notched out as at 8 to receive the end portions of the cross bar 9. Obviously, when the cross bar 9 which is secured as at 10 to the cap 6 is engaged into the notches 8 it can ride against the lower edges of the flanges 7 and firmly hold the cap 6 in place. However, it is a simple matter to remove these caps without locking means and in carrying out the present invention, the lock means generally referred to by numeral 11 is employed. This consists of the frame structure 12 disposed outwardly from the shell formation 13 on the side of the neck 5. The frame 12 is provided with the cross member 14 through which the armature 15 is slidable. The armature 15 is also slidable through the end plate 16 of the frame 12 and into the shell 13. The other end of the armature 15 has the head 17 thereon opposed to the adjacent end of the core 18 of the electro-magnet generally referred to by numeral 19. This electro-magnet 19 has the pair of windings 20—21 thereon.

60 The cap 6 has a leg 22 depending therefrom and into the shell 13 so that when the cap has

been secured in place with the cross bar 9 engaging under the flanges 7—7 and the leg is to the position substantially shown in Figure 3, the presence of the adjacent end of the armature 15 within the shell 13 will prevent return of the leg 5 22 and obviously prevent removal of the cap 6 until the armature 15 has been retracted. The spring 23 on the armature 15 serves to maintain the armature in the projected position shown in Figure 3 and it can only be retracted when the 10 switch generally referred to by numeral 24 has been actuated by a suitable manual control 25, for energizing the coils 20—21.

As can be seen in Figure 6, numeral 26 denotes the source of current such as a battery connected 15 by the lead 27 to the contact 28 of the switch 24. Extending from the contact 29 of the switch 24 is the conductor 30 to the coil 20, while the other side of the coil is grounded. A contact 31 located opposed to the contacts 28—29 is connected by 20 the jumper 32 to the winding 21.

It can be seen, that the switch plate 33 is pushed from a position bridging none of the contacts to a position in the first instance bridging all three contacts and resulting in the momentary energization of both windings of the electromagnet.

30 However, when the plate 33 has moved so that only the contacts 28—29 are bridged, one of the windings, namely, the winding 21 will become de-energized, leaving only the winding 20 to hold the armature 15 in retracted position. While the foregoing specification sets forth the invention in specific terms, it is to be understood that numerous changes in the shape, size and materials may be resorted to without departing from the spirit and scope of the invention as claimed 35 hereinafter.

Having described the invention, what is claimed as new is:

40 A latch structure of the character stated comprising a shell, an end wall for the shell, a cross member in the intermediate portion of the shell, a frame extending longitudinally in the shell, said frame including narrow elongated members, 45 said frame members being connected together at one end of the frame, said end wall having its edge portion notched to receive the remaining ends of the frame members, a latch member slidably disposed through the end wall and through 50 the cross member, a spring connected at one end to the latch member and being adapted to project the latch member in an outward direction, a head at the inner end of the latch member and an electro-magnet on the inner end of the frame 55 where the elongated narrow members are connected together and in electromagnetic relation with the head at the inner end of the latch member.

FRANK MACAGNO. 60
